UNITED STATES PATENT OFFICE.

JOHN J. CAIN, OF BAYONNE, NEW JERSEY.

LOCOMOTIVE BOILER.

Application filed September 25, 1920. Serial No. 412,806.

To all whom it may concern:

Be it known that I, JOHN J. CAIN, a citizen of the United States, and a resident of Bayonne, county of Hudson, State of New Jersey, have invented new and useful Improvements in Locomotive Boilers, of which the following is a specification.

This invention relates to steam boilers, comprising narrow hollow chambers or sections transversely arranged with vertical passages between their heat receiving opposed surfaces and an equalizing chamber connected to their steam spaces, particularly to the application of a boiler so characterized to a locomotive.

An object of the invention is to embody in a locomotive boiler features of construction that will, for a given size, provide maximum heating capacity, capable of withstanding desired maximum operating pressures and at a minimum cost to manufacture and of upkeep expenses. To this end the size of sections, determined by the largest dimensions, is such as to occupy substantially the whole 25 of the area bounded by the vertical and transverse horizontal dimensions of the available space of the locomotive above its running gear. The length of a boiler of this invention is much less than that of a locomotive boiler of the usual type having the same steaming capacity, thus leaving considerable unoccupied space at the front end of the locomotive. This space, or part of it, may be occupied by additional sections applied to the front end of the boiler when it is desired to increase the power or steaming capacity of the boiler, the number of said added sections being commensurate with the desired increase of boiler power. The space 30 at the front of the boiler may be utilized to hold the accessories of the boiler, as for instance the air pumps, sand boxes, tools, &c.

To fully describe the invention reference will now be had to the accompanying drawings, in which:

Fig. 1, is a longitudinal view of the boiler applied to a standard type of locomotive, the running gear of which is represented by dotted lines.

Fig. 2, is a transverse section of the same through the furnace of the locomotive.

Fig. 3, shows the lower parts of a few of the sections of the boiler and means for connecting them to a longitudinal girder of the boiler supporting frame.

Fig. 4, is an end view of Fig. 3.

Fig. 5, is a transverse section, on line 5, 5, Fig. 7, illustrating a method of using some of the boiler sections for superheating the steam.

Fig. 6, is a plan view of said superheater sections and their connections and appurtenances, and

Fig. 7 is a side view of the superheater sections shown in Fig. 5, and one of the furnace sections of the boiler and a baffle plate or wall.

In applying a boiler of this invention to a locomotive a suitable frame is provided, consisting of strong rigid longitudinal side 70 girders adequately braced together and secured to the frame of the running gear 8 of the locomotive. These girders are vertically offset, the lower parts 9 being at the sides of the furnace and the higher parts 75 10 extend forwardly practically the full length of the locomotive; they are preferably composed of I beams 11, and channel irons 12, rigidly secured to the tops of the I beams, see the enlarged views, particularly 80 Figs. 3 and 4.

The sections of the boiler are substantially all alike and are narrow hollow chambers with their largest dimensions transversely arranged in the boiler, their side areas being such as to occupy all of the space bounded by the available vertical and horizontal transverse measurements of the locomotive above its running gear. See Figs. 1 and 2.

The sections are spaced apart to afford passages between them for the hot gases from the furnace; they are preferably horizontally corrugated to strengthen them, to compensate for variations of temperatures and, by the sinuosity of the passages to increase heating effects.

The transverse sections are, for manufacturing reasons, preferably in two parts, arranged in pairs, right and left in the boiler with their inner central edges adjacent; the surface of each pair being substantially equal to and covering the transverse area determined by the height and transverse horizontal measurements of the available space of the locomotive above its running gear.

The sections 13 at the furnace end of the boiler are formed with water legs 14, by which they are supported on the portions 9 of the girders and they are here widened so as to be close together to constitute the side walls of the fire box, or portions thereof.

From the water legs the edges of these sections extend upwardly in arch form towards the center of the boiler, forming the crown of the fire box. The forward or other series 5 of sections 15, rest at their lower edges on the portions 10 of the girders and their under edges, which are arch shaped similar to the series 13, are sufficiently high above the bottom of the boiler to provide a suitable combustion chamber 16. This space 16 may be used as a continuous combustion chamber 10 affording communication to all of the vertical passages between the sections 15 for the hot gases from the furnace that do not 15 pass upwardly through the passages of the sections 13; but when the boilers are made of considerable length it is proposed to divide said chamber into compartments by an enclosing baffle or wall 54, filling the space 20 between the bottom of the chamber and the underside of the sections a suitable distance from the fire box.

The adjacent sections of each set 13 and 15 are coupled together by expanded nipples 17 and 18 respectively at their lower 25 parts, affording free water communication between them.

With the wall 54 located as above described all of the gaseous products of combustion will first flow upwardly between the sections at the rear of said wall, then along the communicating passage 55, at the top of the boiler, and down the passages of the sections into the portion of the chamber 16 30 immediately in front of the wall 54, being so directed by a baffle plate or wall 56, suitably located in the passage 55. From the forward division of the chamber 16 the gases ascend through the passages of the foremost sections into the front end of the top passages 55 and hence through the chimney 51. The boiler is thus divided into three passes, restricting the flow of the gases 35 by increasing the line of travel and insuring a more perfect distribution of the heating effects of the hot gases than if said baffles 54 and 56 be omitted. Of course the number of these baffles and their locations will be determined by the size of and particular requirements of the boiler to which 40 they are applied. The baffle walls 54 and 56, form extensions of the bottoms and tops respectively of the sections to which they are applied, the sides of said sections being in no way interfered with as heating surfaces. The said sections may be increased in vertical dimensions to control the flow of the gases through the combustion chamber 16, and smoke passage 55, as described.

60 The upper parts of the sections above the water level, really constituting a steam dome for each section, should for practical operative purposes be connected to an equalizing chamber. For this purpose it is preferred to use a drum 19, extending the full length

of the boiler and located in a cylindrical space formed by circular recesses 20, made in the upper edges of the two sets of sections. This drum is securely fastened to all of the sections and thereby holds them firmly 70 in place, by nipples expanded in opposed holes; the lower nipples 21 connect the water spaces of the drum and sections, the central nipples 22, located at the water line of the boiler, connect both the water spaces and the steam spaces and the upper nipples 23 connect the steam spaces of the drum and sections.

Water will preferably be supplied to the boiler by a perforated pipe 24 placed in the 80 lower part of the drum 19. Fresh water will thus enter the sections from the drum by the nipples 21, and flow down the interiors of the sections towards the parts exposed to the greatest heat, insuring perfect 85 circulation throughout the sections.

The upper parts of the adjacent sections 90 may be connected together by expanded nipples if desirable.

In many or most cases modern engineering practice calls for superheated steam and the special features and ensemble of this boiler adapts it to produce superheated steam at little trouble and expense. One, 95 and the preferred method of accomplishing this is to use some of the sections, without any material changes, that are located in any suitable part of the boiler. Any requisite or desired number of sections may 100 be so used: see Figs. 5, 6 and 7.

The boiler, as a whole, is supported on and securely fastened to the side girders 9 and 10; a suitable method for accomplishing this being by bolts 25, which are passed through holes in the channel irons 12 and in flanges 26 formed on the lower ends of the sections. These flanges extend from the front and rear sides of the sections, where they are spaced apart, so to abut, thus adding rigidity to the structure.

27 designates the furnace, 28 the grate bars, 29 one of the furnace doors, 30 the ash pit and 31 the cab of the locomotive.

The steam may be utilized directly from the drum 19 by allowing it to pass to the engine through the dry pipe 32, but generally a superheater will be used. This may consist of pipes 33 extending the full length of the boiler and arranged adjacent the upper part of the drum and joined at one end to the dry pipe by a T connection 34, in the cab of the locomotive; their other ends being joined by a similar T 35, at the front end of the boiler, from which steam will pass to the engine. The cab connection 34 is shown provided with a throttle valve 36. It is proposed however to utilize some of the sections as a superheater, thus avoiding making and installing a special superheater; these selected sections may be located in any 110 115 120 125 130 suitable part of the boiler, as for instance some of the set of sections 15 just in front of the furnace sections 13. As shown in Figs. 5, 6 and 7, in which three pairs of sections 15 are converted into a superheater; they are secured, as are the other sections 15, to the girder 10 by bolts and flanges 25 and 26. They are also secured to the drum 19 by nipples 21, 22 and 23; the nipples 21 and 22 being closed in any suitable manner, as for instance by caps 38. These superheater sections are thus isolated from the other sections of the boiler.

The adjacent faces of the lower parts of the sections 37 may be connected together by nipples 39.

The dry pipe 32, in this case, which may extend practically the whole length of the drum has its only outlets by the branches 40 connected to the nipples 23 at the upper parts of the superheater sections 37. As the outlets of the superheater sections are located most conveniently at their upper parts nipples 41 connect them to boxes 42, and to insure proper circulation of the steam throughout them they are provided with partitions 43, 44. The partitions 43 have their upper ends in contact with the tops of the sections and their lower ends a short distance from their bottoms, so as to act as deflectors to direct the steam downwardly. The other partitions 44, short both top and bottom, act as baffles to assist in distributing the steam in the sections.

The steam passes from the superheaters to the main supply pipe 45, which extends to the engine, from the boxes 42 by cross pipes 46 connecting said boxes to a throttle valve 47, formed with a base to seat on the drum 19. The main steam pipe 45 connects with the throttle valve and the valve is operated by a rod 48, which extends to the cab of the locomotive and is there under the control of the engineer through the medium of any suitable operating means, the construction and functions of which will be well understood.

The safety blow-off is preferably applied to the superheating system, it may consist of a valve 49, horizontally arranged and connected to each of the cross pipes 46, with a discharge opening at its upper side.

A casing 50, of sheet iron and insulating material, surrounds or covers the boiler, its top being a sufficient distance from the top of the boiler to provide a passage 55 for the free flow of the hot gases passing upwardly through the spaces between the sections to the smoke stack opening 51.

Openings 52 in the top of the casing surround the safety valves 49. The casing will also be provided with cleaning doors suitably located at the top, sides and bottom.

The casing 50 is shown the full length of the locomotive frame, a considerable dis-

tance beyond the front of the boiler, leaving a space or room 53 at the front end of the locomotive; see Fig. 1, which illustrates a sectional boiler of this invention of a length to provide as much or more steaming capacity than a regular type of locomotive boiler that would occupy about all of the space longitudinally available on a locomotive. This room or space 53 may be utilized to hold the air pumps, sand boxes, tools, &c., and other appurtenances of the locomotive. Access to this room may be had through the door way 57.

The vertical offset of the two parts 9 and 10 of the side girders may be made by adequately heavy and strong angle or splicing plates 59, see Fig. 7.

It will be understood that the steaming capacity of this boiler may be increased to any desired extent by the addition of sections 15 to the forward end of the boiler, the drum 19, of course being correspondingly lengthened, and still leaves sufficient room in the space 53 for the purposes indicated. This room may also be used as the cab in cases where it is deemed advisable or expedient to locate the engineer at the front of the locomotive.

High steam pressures, now generally desired, may be carried by the boiler of this invention without calling for excessive or undue weight as results in attempting to attain this end with the present type of locomotive boilers. The comparative thin hollow sections, whether made of cast or wrought metal, may be strengthened to resist any practical working pressures by braces, preferably consisting of short pieces of tube passed through and expanded in the sides of the sections, as indicated at 58, Fig. 2.

I claim:

1. A locomotive boiler, comprising similar narrow hollow vertical sections, having supporting feet at their lower edges transversely arranged edgewise in pairs with their adjacent edges at the longitudinal central plane of the boiler and spaced apart to provide continuous vertical heating passage between them, the boundaries of the transverse faces of each pair being substantially equal to the vertical and transverse horizontal boundaries of the available space of the locomotive above its running gear, said duplex sections being in two sets longitudinally located in the boiler, the lower parts of the sides of the set of sections at the furnace end of the boiler being water legs and constituting the side walls of the fire box with their supporting feet at a lower level than those of the other set of sections, in combination with the main frame of the locomotive to the side girders of which the supporting feet of the sections are secured.

2. A locomotive boiler, comprising narrow

hollow sections, having arch formed bottoms and flange supporting feet at their lower outer edges, transversely arranged in the boiler and spaced apart to provide heating 5 passages between them, the boundaries of their continuous transverse faces being substantially equal to the vertical and transverse horizontal boundaries of the available space of the locomotive above its running gear, 10 the main frame of the locomotive to which the supporting feet of the flanges of the sections are secured, and steam collecting means longitudinally centrally arranged and connected to the steam spaces of all of the sections. 15

3. A locomotive boiler, comprising similar narrow hollow sections, having supporting feet at the ends of their lower edges, transversely arranged in the boiler and 20 spaced apart to provide heating passages between them, the boundaries of their transverse continuous faces being substantially equal to the vertical and transverse horizontal boundaries of the available space of the 25 locomotive above its running gear, a superheater composed of some of the sections, steam collecting means connected separately to the water spaces and the steam spaces of all of the sections other than the superheating 30 sections and pipe connections joining said steam collecting means to the superheating sections only, in combination with the main frame of the locomotive to which the supporting feet of the sections are secured. 35

4. A locomotive boiler, comprising narrow hollow sections transversely arranged in the boiler and spaced apart to provide vertical heating passages between them, an equalizing chamber extending the full length of the boiler in communication with the steam spaces of the sections, a furnace beneath some of the sections at the rear end of the boiler, said furnace sections having water 45 legs constituting the sides of the fire box, a combustion chamber extending from the furnace to the front end of the boiler beneath the other sections, at a higher level than the furnace grate, the main frame of the running gear of the locomotive to which the lower outer edges of all of the sections are secured and a passage with a chimney outlet at the top of the boiler into which all of the vertical heating passages open. 50

5. A locomotive boiler, comprising narrow hollow sections transversely arranged in the boiler and spaced apart to provide vertical heating passages between them, an equalizing chamber in communication with the steam spaces of the sections, a furnace beneath some of the sections at one end of the boiler, a combustion chamber beneath the other sections and extending to the other end of the boiler, a passage at the top of the boiler open to all of the heating passages, 55

a baffle plate or wall athwart the combustion chamber in continuation of one of the sections to cause the products of combustion to first pass through the heating spaces of the sections at the rear of said wall adjacent 70 the furnace, a baffle plate or wall athwart the top passage, in advance of the lower baffle plate and resting on the top of another section, to direct said gases downwardly through another set of sections into the 75 forward part of the combustion chamber and hence upwardly between the third set of sections into the forward part of the top passage, which is provided with a chimney opening. 80

6. A locomotive boiler, comprising narrow hollow sections, similarly formed, transversely arranged in the boiler and spaced apart to provide heating passages between them, the boundaries of their transverse continuous faces being substantially equal to the vertical and transverse horizontal boundaries of the available space of the locomotive above its running gear, the length of the boiler being less than that of the available space above the running gear, a furnace at the rear end, a combustion chamber extending forwardly from the furnace beneath the sections, a passage at the top of the boiler open to all of the heating passages, 90 a chimney opening at the front end of said passage extending upwardly therefrom and a casing surrounding the boiler. 95

7. A locomotive boiler, comprising narrow hollow sections in three groups transversely arranged in the boiler and spaced apart to provide heating passages between them, a superheater composed of the middle group of sections, a drum longitudinally arranged, connecting passages between the 100 water and steam spaces of the drum and sections other than the superheating sections, a dry pipe in the drum and branch pipes from the dry pipe to the superheating sections. 105

8. A locomotive boiler, comprising narrow hollow sections in three groups transversely arranged in the boiler and spaced apart to provide heating passages between them, a superheater composed of the middle group of sections, a drum longitudinally 110 arranged, connecting passages between the water and steam spaces of the drum and sections other than the superheating sections, a dry pipe in the drum, branch pipes from the dry pipe to the superheating sections, a smoke passage over all of the sections into which all of the heating passages open, a box connected to the superheating sections, a throttle valve and a pipe connection between the box and the throttle valve located 115 in the smoke passage. 120

9. A locomotive boiler, comprising narrow hollow sections transversely arranged in the boiler and spaced apart to provide heating passages between them, a super- 125

heater composed of some of the sections, a drum longitudinally arranged, connecting passages between the water and steam spaces of the drum and sections other than the superheating sections, a furnace beneath some of the sections at one end of the boiler, a combustion chamber beneath the other sections extending to the other end of the boiler, a smoke passage over the sections into which all of the heating passages open, a dry pipe in the drum, branch pipes from the dry pipe to the superheater sections and a horizontal safety valve connected to the superheater and located in the smoke passage.

10. The combination with the running gear of a locomotive of a longitudinal girder secured to each side of the frame thereof of a boiler comprising narrow hollow sections transversely arranged and spaced apart to provide heating passages between them, a drum longitudinally arranged and in communication with the water and steam spaces of the sections and means for securing the outer lower edges of each section to the girders.

11. The combination with the running

gear of a locomotive of a vertically offset longitudinal girder secured to each side of the frame thereof of a boiler comprising narrow hollow sections transversely arranged and spaced apart to provide heating spaces between them, a drum longitudinally arranged and in communication with the water and steam spaces of the drum and sections, means for securing the outer lower edges of each section to the girders, a furnace between the lower portions of the offset girders over which some of the sections are located, a combustion chamber extending forwardly from the furnace along the bottom of the boiler at the high portions of the offset girders and over which the balance of the sections are located and a chimney provided passage at the top of the boiler into which all of the passages between the sections open.

Signed at New York, county and State of New York, this 22nd day of September 1920.

JOHN J. CAIN.
